UNITED STATES PATENT OFFICE

2,605,005

GOLF BALL RETRIEVING DEVICE

Walter Wenzel, Oconomowoc, and Edmund Greenwald, Milwaukee, Wis.

Application September 6, 1950, Serial No. 183,320

4 Claims. (Cl. 214—65)

1

Our invention relates to retrieving machines, and more particularly to a device for picking up golf balls from driving ranges or the like.

The object of our invention is to provide a device that lifts the balls from the ground by rotatable centrifugal action.

Another object of our invention is to provide a device of the character described that rotates the ball by centrifugal frictional means during elevation from the ground, without applying any clamping force to the ball.

Still another object of our invention is to provide a device that eliminates the danger of fracturing the outer cover of the ball being retrieved.

A further object of our invention is to construct a device in a manner to provide access to the golf balls scattered over an uneven terrain.

A still further object is to provide a device of the character described that will permit access to the entire surface onto which the golf balls have been deposited, and in which the balls are directed towards the rotating elevator units.

Still another object of our invention is to eliminate the possibility of the device forcing the ball into the soft ground during the process of retrieving.

The device employs a principle entirely different from the prior art, is easy to manipulate, and is highly efficient for the purpose for which it is intended.

It is manifest to anyone familiar with the art of retrieving golf balls from driving ranges or the like, that it is often times quite difficult to reach the balls deposited in recesses within the terrain or uneven surfaces of the field, and the conventional method of discs employed, creates the hazard of fracturing the spherical, peripheral surface of the ball due to the clamping of the ball by means of friction between rotating disc members. Our device eliminates all these hazards inasmuch as the balls are rolled against both sides of the rotating members, and are conveyed by means of a rolling action between the walls of the semicircular grooves of the conveyer members, and guided upwardly between the conveyer and the semi-circular stationary guide wings which are equipped with corresponding semi-circular grooves.

Other and further objects of our invention will become more apparent as the description proceeds, when taken in conjunction with the drawings in which:

Figure 1 is a top or plan view of the entire device.

Figure 2 is a side view of an assembled re-

trieving unit showing the ball guide in cross section.

Figure 3 is a fragmentary perspective view of the retrieving unit.

Figure 4 is a cross-section of the conveyer unit and guide wings mounted on a shaft, and showing a golf ball positioned within the oppositely disposed semi-circular grooves.

Figure 5 is an enlarged top or plan view of an assembled retrieving unit hingedly supported on a portion of the cross bar, and

Figure 6 shows a basket or receptacle for supporting and conveying the retrieved balls.

Similar characters of reference indicate corresponding parts throughout the several views, and referring now to the same, the character 10 shows a cross bar which is longitudinally disposed and which is provided with a yoke 11, which yoke is attached at its ends to the cross bar at 12, and has a shackle arrangement 13 for attachment to a vehicle (not shown) while the entire device is being propelled over the ground. The shackle, obviously, is shown equipped with an aperture 14 for the engagement of the attaching means.

The device may either be pushed or pulled over the terrain from which the golf balls are being retrieved. The end support members 15, attached at 16 to the cross bar 10, are of rigid construction, and we show a plurality of hinged members 17, having pivoted arms 18, attached thereto by means of pivot brackets 19 having apertures 20, and these brackets are attached to the arms 18 at 21 in any convenient manner.

There are hinge members 17 attached to the cross bar 10 at 22, and pins 23 extending through the brackets 19 and the hinge members 17 act as a fulcrum for the entire separate unit. The pivoted arms 18 are attached at 29 to the frame structure 25 which is in the form of a spider member, supporting guide wings shown as 26, which are stationary and have semi-circular grooves 27 on their inner face. The outer face of the guide wings 26 are shown provided with vertical channel members 28, having loop members 29, at their upper end, and having outwardly disposed contact members 30 which are placed angularly so that their depending end 31 is forward from the point of the attachment to the vertical members 28.

The contact members 30 have horizontal flat sections 32 at their top. There are downwardly disposed members 33 attached to the pivoted arm 18 at 34, and the lower end of these members 33 support a blade shown as 35 which contacts the

ball 36 disposed on the ground in the path of the rotary conveyers 38 and moves it sideways in either direction for engagement with the contact member 30.

The spider members 25 act as bearings for the ends of a shaft 37 onto which is rotatably mounted the rotary conveyor 38 which has a flat surface 39 on its outer periphery, and has concave semi-circular grooves 40 on each of its sides. These semi-circular grooves 40 on the rotating conveyor are directly opposite to the semi-circular concave grooves 27 in the guide wings 26.

Baskets or containers shown as 41 in Figure 6 are provided with hook members 42 for engagement with the arms 18, and another set of hook members 43 for engagement with the loop 29, at the top of the vertical member 28. These baskets are supported in position as shown in Figure 1.

In operation, the entire assembly is propelled over the surface of the ground by means of a vehicle (not shown). It may, of course, be pulled or pushed, the flat surface 39 on the periphery of the rotating conveyors 38 contact the ground, and the entire device is supported by the two outer rotating conveyors shown as 38 which are rigidly supported at 16 to the cross bar 10, leaving the rest of the plurality of conveyor units 38 free to move up and down due to the pivoted support by means of the pin 23 on the hinge member 17. The conveyors 38 are rotatably supported by the shaft 37 which is journalled within the spiders 25, and have guide wings 26 disposed on each side thereof. The lower ends of the semi-circular guide 27 have outwardly extending contact members 30 which reach out their ends 31 toward one another. In this manner, as the conveyors 38 and 38 move over the ground, the angularly disposed contact members 30 will cause any ball 36 coming in contact therewith to be rolled toward the semi-circular groove 40 on both sides of the rotating conveyor 38, and the semi-circular grooves 27 of the guide wings 26. Due to the centrifugal force exerted by the rotating conveyor, the ball will roll against the wall of the groove 27 causing the ball to keep rolling at all times due to contact with the inside of the grooves 27 and 40 until the ball 36 reaches the top of the semi-circular wing 26, at which time, it will be free to drop into the basket 41. The ball, as it is being conveyed from the lower opening to the upper opening, rolls at all times, due to the rotation of the conveyor unit. Obviously, the basket or container 41 may have a partial cover, or may be constructed of any shape or contour to prevent the balls that have been retrieved from bounding out of the basket or the like.

It is manifest therefore that our device has many advantages inasmuch as the principle involved is to guide the ball disposed on the surface of the ground, no matter how uneven the terrain may be, toward the revolving members which are provided with a receiving means on both sides thereof, and the ball is raised by centrifugal force and rotatable friction resistance between the revolving member and the stationary semi-circular wing members, toward the upper end of the wing where it is free to be deposited into a receptacle or container.

The ball is never wedged between two objects, is never subjected to the hazard of having its spherical, peripheral surface grooved or cut, for it is rotated during its entire travel upward.

The entire assembly may be made into one unit or a plurality of units, and is constructed so that every radial revolving member is independent of the other, and acts as its own means of reaching the ground level. Obviously, any number of balls may be disposed at one time within the grooves, without interfering with one another.

In the chosen embodiments of our invention exemplified by the accompanying drawings, there are many features that identify it from the existing art, and although we have shown a specific structure, we are fully cognizant of the fact that the component parts may vary in shape and contour, and we reserve the right to make such changes without departing from the spirit of our invention or the scope of the appended claims.

Having thus described our invention, what we claim and desire to secure by Letters Patent in the United States is:

1. A ball retriever of the character described comprising, a cross member having a plurality of transverse members pivotally attached thereto, a plurality of said transverse members rigidly attached to said cross members, said transverse members having rotating conveying members rotatably mounted to their outwardly projecting ends, stationary members attached to said transverse members, said stationary members spaced apart from said rotating members and adjacent thereto, said rotating conveyor members provided with continuous semi-circular concave grooves in both of their outer flat surfaces, said stationary members provided with semi-circular concave grooves of semi-angular contour disposed on their inner faces, said grooves in said rotary conveyor member and stationary member being placed in direct alignment with one another, outwardly extending guide members attached to and adjacent to said stationary member at the lower open portion of the semi-circular groove in said stationary member, a blade member attached to said stationary members, said blade member extending across the peripheral face of said conveyor, in alignment with said guide member, and a plurality of receptacles attached to said transverse members for retaining balls elevated by said rotating conveying member.

2. A ball retrieving device of the character described comprising, a longitudinal cross member, a plurality of transverse members attached to said cross member, some of said transverse members provided with a hinge member for pivotally supporting said transverse members to said cross members, all of said transverse members having rotating conveyor members mounted to their outwardly projecting ends, stationary members attached to said transverse members, said stationary members spaced apart from said rotating members and adjacent thereto, said rotating conveyor members provided with a continuous semi-circular recessed groove on both of its outer faces, said stationary members provided with semi-circular recessed grooves of semi-circular contour disposed on their inner faces, said grooves in said rotating conveyor member and stationary member being in direct alignment with one another, outwardly extending guide members attached to the stationary members adjacent to the lower open portions of the semi-circular grooves in said stationary member, a blade member attached to said stationary member, said blade member extending

across the peripheral face of said rotary conveyer in alignment with said guide members, and a plurality of receptacles attached to said transverse members, said receptacles arranged in a manner to receive the balls that have been elevated by said rotating conveyor members due to their rotating frictional contact between said rotating and stationary members.

3. A ball retrieving device of the character described comprising in combination, a longitudinal cross bar, said bar supporting a plurality of transversely attached retrieving units which are permitted to move independently from one another, said retrieving units consisting of a rotatably mounted rotating conveyor, journaled to said transverse units, a pair of semi-circular stationary members each rigidly supported on opposite sides of said rotating conveyor, said rotating conveyor being provided with continuous circular recessed grooves on each of its outer faces, said stationary members provided with a semi-circular recessed groove open at its bottom and top and in direct alignment with the continuous semi-circular groove in said rotating conveyor, guide members extending outward from the bottom of said stationary member at the bottom of the opening thereof, said guide members extending in angular relation to said stationary members, and a receptacle attached to said unit near the outlet of the semi-circular groove in said stationary member to receive the balls conveyed upward within said grooves due to the rotatable frictional contact of said balls with the face of the inner walls of said grooves.

4. A ball retrieving device of the character described comprising, a longitudinal cross bar, said bar supporting a plurality of transverse retrieving units which are hingedly supported by said cross bar and free to move up and down independently one from the other, said retrieving-

ing units consisting of a rotatably mounted conveyer journaled to said transverse unit, a pair of semi-circular stationary members, each rigidly supported on opposite sides of said rotating member, the rotating members being provided with continuous circular recessed grooves on both of its outer faces near its peripheral edge, said stationary members provided with semi-circular recessed grooves open at the top and bottom and in direct alignment with the continuous groove in said rotating conveyer member, a blade member extending across the peripheral face of said rotating member, guide members extending outward from both of said stationary members at the bottom opening thereof, said guide members extending in angular relation to said stationary members, and receptacles attached to said units near the upper outlet of the semi-circular groove on said stationary members to receive the balls conveyed upward within said grooves due to the rotatable frictional contact of said ball with the inner face of the walls of said groove.
